UNITED STATES PATENT OFFICE.

LOUIS J. HUGUES, OF TOPEKA, KANSAS, ASSIGNOR OF ONE-HALF TO O. F. MARCOTTE,
OF TOPEKA, KANSAS.

HYDRAULIC TRANSMISSION.

1,396,756.

Specification of Letters Patent.

Patented Nov. 15, 1921.

Application filed December 20, 1919. Serial No. 346,255.

To all whom it may concern:

Be it known that I, LOUIS J. HUGUES, a citizen of the United States, residing at Topeka, in the county of Shawnee and State of Kansas, have invented new and useful Improvements in Hydraulic Transmission, of which the following is a specification.

This invention relates to transmission means particularly adapted for automobiles for transmitting the motion of the drive shaft to the driven shaft.

The principal object of the invention is to provide means for entrapping a substantially wedge-shaped body of fluid between the driving member and the driven member so that the motion of the said driving member will be imparted to the driven member by this body of fluid.

Another object of the invention is to provide means for controlling the escape of fluid from between said members so as to impart different speeds to the driven member while the driving member is actuating at one speed.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a longitudinal sectional view of the invention.

Fig. 2 is a cross section on line 2—2 of Fig. 1.

Fig. 3 is a section on line 3—3 of Fig. 1.

Fig. 4 is a section on line 4—4 of Fig. 1.

Fig. 5 is a view of the sliding sleeve or controlling member.

Fig. 6 is a detail view.

In these views 1 indicates the casing which is formed of two parts connected together by the bolts 2. The ends of this casing are provided with the bosses 3, through one of which passes the driving shaft 4 and through the other the driven shaft 5. This driving shaft, within the casing, carries the abutments 6 and the driven shaft 5 has secured thereto, or formed therewith, the cylinder 7 which incloses said abutments.

The end of this cylinder is closed by the cover 8 which is provided with the central opening 9 to receive the shaft 4. The end of shaft 4 fits within a recess 10 formed within the shaft 5 at the point of junction with said shaft. It will thus be seen that the shaft formed with its abutments may have rotary movement within the cylinder. Eccentric rings 11 are placed within the cylinder and secured to the walls thereof by the screws 12 and these rings are spaced apart to form circular chambers in which the abutments rotate. Ring-shaped members 13 are eccentrically placed in said cylinder with their reduced side edges 13' engaging the stationary rings 11. The central parts of these members 13 bridge the chambers formed by said eccentrics 11 and each ring member is provided with an opening 14 through which one of the abutments passes. Thus as the shaft and abutments rotate the ring members 13 will be rotated with them. As will be seen the ring members 13 are in contact with a part of the cylinder so that as the abutments reach this point of the cylinder, said 75 abutments will have their ends flush with the walls of the ring members or in other words said abutments will be entirely within said ring members. Upon the continued rotation of the parts the abutments will gradually project from the ring members and sweep around the chambers and said abutments and ring members will divide the chambers into two parts which are entirely separated from each other as soon as the 80 abutments pass out of the ring members.

I provide outlet openings 15 and inlet openings 16 in the walls of the cylinder, these openings communicating with the chambers and being located adjacent the 95 points of contact of the ring members with the cylinder. The inlet openings are separated from the outlet openings by said ring members so that the fluid must pass around the ring members to get to the outlet openings.

In order to control these ports or openings I provide a slide sleeve 17 which embraces the cylinder and is provided with outlet ports 18 and 19 for co-operating with the 105 outlet ports 15 of the cylinder and with an elongated inlet port 20 for co-operating with the inlet ports 16 of said cylinder.

This sleeve is provided with a pair of spaced flanges 21 which receive the rollers 110

22 carried by the ends of the yoke 23, the stem 24 of this yoke passing through a suitable stuffing box in the end of the casing. In this way the sleeve may be adjusted in 5 position on the cylinder to control the passage of fluid through the ports.

It will be understood that the fluid in the casing is under pressure so that it will pass into the cylinder when the ports are opened. 10 The casing is provided with a pressure valve 25 and a drain plug 26. Spring controlled pressure rings 27 prevent leakage at the bosses.

When the ports are opened and the drive 15 shaft is being rotated the fluid will pass into the cylinder through the inlet ports and will be carried around by the abutment to the opposite side of the cylinder where it will flow from the outlet ports. If the outlet ports 20 are restricted or entirely closed by the sliding sleeve the body of fluid in front of the abutment will assume a substantially wedge-shape between the ring members 13 and the walls of the cylinder so that said cylinder 25 will be caused to rotate with the shaft and abutments. By adjusting the size of the outlet ports by the sliding sleeve various speeds may be given to the cylinder without changing the speed of the drive shaft. If 30 the outlet ports are entirely closed the cylinder will be rotated at the same speed as the drive shaft and in order to prevent the heating of the fluid under the continuous pressure I provide means for locking the 35 cylinder to the drive shaft when the two parts are to rotate as one. Such means consists of a slideable member 28 having an offset part 29 provided with a curved face and an inclined face. The curved face is adapted 40 to engage with an eccentric 30 formed on the end of the shaft 4 and the inclined face is engaged by the inclined end of a longitudinally movable lever 31 which has its upper end provided with a neck 32 which engages a slot 33 formed in the sleeve 17. The 45 part of the sleeve in which the slot 33 is formed is inclined so that as the slide is moved the member 31 will be moved longitudinally so that its inclined end engaging the inclined face of the offset part 29 will 50 move said member 28 into and out of engagement with the eccentric. The members 28 and 31 are held in position against the end of the cylinder by the ring 34. When 55 the curved face of member 28 is held in engagement with the eccentric on the shaft the cylinder is locked to the shaft and the two parts are rotated as one.

In order to reverse the rotation of the 60 cylinder I provide an annular rack 35 on the cover 8 and a gear 36 on shaft 4 and a sliding gear 37, mounted on a pin 38, carried by the casing, is adapted to mesh with said gear 36 of the rack and in this way 65 rotate the cylinder in the reverse direction.

This gear 37 is moved into and out of operating position by means of the rod 39 having its bent end engaging a groove 40 in the gear.

In this way the cylinder and its shaft may 70 be rotated at various speeds by the drive shaft by the adjustment of the sliding sleeve 17. When the two parts are to be driven at the same speed they are locked together by moving the sliding sleeve to its inner position and when the automobile is to be reversed the rod 39 is moved to bring the gear 37 into mesh with the gear 36 and rack 35. 75

It is thought from the foregoing description that the advantages and novel features 80 of my invention will be readily apparent.

I desire it to be understood that I may make changes in the construction and in the combination and arrangement of the several parts, provided that such changes fall 85 within the scope of the appended claims.

What I claim is:—

1. An apparatus of the class described comprising a driving shaft, an abutment thereon, a driven shaft, a cylinder thereon receiving said abutment, a casing surrounding said parts and adapted to contain fluid, inlet and outlet ports in the cylinder for permitting the fluid to pass thereto, means for controlling said outlet ports and an eccentrically arranged hollow member within the cylinder and surrounding a part of the driving shaft and movable with the abutment and acting with the abutment to divide the cylinder into two parts during a part 100 of the rotation of the abutment. 95

2. An apparatus of the class described comprising a casing containing fluid under pressure, a drive shaft having one end projecting into said casing, an abutment on said shaft, a driven shaft projecting into said casing, a cylinder on said driven shaft and surrounding the driving shaft and its abutment, eccentric rings secured to the walls of the cylinder and spaced apart to form an annular chamber to receive the abutment, a ring member rotatably supported by said eccentric rings and having an opening therein for the abutment and means for controlling the passage of fluid from said chamber. 110 105

3. An apparatus of the class described comprising a casing containing fluid under pressure, a drive shaft having one end projecting into said casing, an abutment on said shaft, a driven shaft projecting into said 115 casing, a cylinder on said driven shaft and surrounding the driving shaft and its abutment, eccentric rings secured to the walls of the cylinder and spaced apart to form an annular chamber to receive the abutment, a ring member rotatably supported by said eccentric rings and having an opening therein for the abutment and adjustable means for controlling the passage of fluid from said chamber. 120 125 130

4. An apparatus of the class described comprising a driving shaft having an abutment thereon, a driven shaft, a cylinder on said driven shaft surrounding the abutment, a casing inclosing said parts and containing fluid under pressure, a ring member eccentrically and rotatably mounted in the cylinder and surrounding the driving shaft and having an opening therein for the abutment, said cylinder having ports therein and means for controlling the passage of fluid through said ports. 35
5. An apparatus of the class described comprising a drive shaft having an abutment thereon, a driven shaft, a cylinder carried by the driven shaft and receiving the abutment, a ring member within the cylinder and eccentrically and rotatably arranged therein and having an opening for receiving the abutment, said member contacting with a part of the inner wall of the cylinder, said cylinder having a port therein on each side of said member and an adjustable sleeve for controlling said ports. 40
- 10 6. An apparatus of the class described comprising a driving shaft, a driven shaft, a cylinder carried by the driven shaft, abutments on the driving shaft within the cylinder, a casing surrounding said parts and adapted to receive fluid under pressure, cam rings secured to the walls of the cylinder and spaced apart to form annular chambers for the abutments, ring shaped members rotatably supported by said cam rings and bridging the chambers and having openings 45 therein for receiving the abutments, said cylinder having ports therein for leading the fluid to the chambers and means for controlling the outlet ports. 50
- 15 7. An apparatus of the class described comprising a drive shaft, an abutment thereon, a driven shaft, a cylinder carried by the driven shaft and receiving the abutment, a ring member eccentrically and rotatably mounted in the cylinder and having an opening 55 therein receiving the abutment, said cylinder having ports therein, a casing surrounding the parts and containing fluid under pressure, means for controlling the outlet ports and means for locking the cylinder to the driving shaft. 60
- 20 8. An apparatus of the class described comprising a driving shaft, an abutment thereon, a driven shaft, a cylinder connected therewith and receiving the abutment, a casing surrounding the parts and receiving fluid under pressure, a ring member eccentrically and rotatably mounted in the cylinder and having an opening receiving the abutment, said cylinder having ports therein, a sliding sleeve for controlling the outlet ports, means controlled by the movement of the sleeve for locking the cylinder to the driving shaft and means for adjusting said sleeve. 65
